UNITED STATES PATENT OFFICE.

WILLIAM S. MAYO, OF NEW YORK, N. Y.

OVERFLOW FOR WATER-CLOSETS.

SPECIFICATION forming part of Letters Patent No. 430,966, dated June 24, 1890.

Application filed January 25, 1890. Serial No. 338,076. (No model.)

To all whom it may concern:

Be it known that I, WILLIAM S. MAYO, a citizen of the United States, residing at New York, in the county and State of New York, have invented new and useful Improvements in Overflows for Water-Closets and other Receptacles, of which the following is a specification.

This invention relates to overflows for water-closets, wash-basins, wash-tubs, and the like; and the invention consists in the details of construction set forth in the following specification and claims, and illustrated in the accompanying drawings, in which—

15 Figure 1 is a sectional view of a water-closet bowl with my invention. Fig. 2 is a sectional view of a wash-basin with my invention, the section being taken along $\alpha\alpha$, Fig. 3. Fig. 3 is a plan view of Fig. 2. Fig. 20 4 is a perspective view of a faucet. Fig. 5 is a section along $\gamma\gamma$, Fig. 4. Fig. 6 is a section along $z z$, Fig. 5.

In the drawings, the letter A indicates a bowl, basin, or receptacle having overflow-25 openings B, through which the overflow-water can pass off. The overflow-water passes into a cup E. This cup is preferably secured to the outside of the receptacle A; but I do not confine myself to this particular arrangement 30 of the cup. The overflow-water passing from the cup E flows through the tube F into the outlet H, which outlet can also serve for taking off the water from the receptacle A. The tube F has a bend or trap G, which keeps a 35 certain supply of water standing in the cup E, so as to prevent foul gases passing through the tube F and out at the openings B.

In Fig. 1 a jet or inlet I is shown leading into the cup E, and when fresh water is supplied to the receptacle A part of said fresh water passes through the inlet I into the cup E, thereby cleansing said cup and keeping the water-supply of said cup fresh and pure.

The inlet or jet I may be variously formed. 45 In Fig. 1 said inlet is a passage leading from the flushing-rim of the receptacle A into the cup E. In Figs. 2 to 6 the inlet I is a branch or jet connected with the faucet K. When said faucet is moved to its open position to fill the 50 receptacle A, the inlet or jet I is temporarily opened, so as to supply a certain amount of fresh water to the cup E. By means of this

inlet or jet I the trap G is kept sealed with fresh water, so as to prevent foul odor or the escape of foul gas from the overflow-pipe. If 55 through long non-usage the water in the cup E is evaporated, the valve or ball L sinks to the bottom or onto the outlet of said cup and closes said cup against the entry of foul gas. When water is in the cup, said ball L floats 60 in the cup, so as to leave any excess of water in the cup free to flow off. The ball L is shown provided with a weight O—such as a drop of mercury, a supply of shot, or the like—which weight presses the ball L firmly 65 into place when said ball is required to close or seal the cup E. When the receptacle A is being emptied, the rush of water through the outlet H might cause emptying or siphonage of the trap G and cup E. To prevent such 70 emptying or siphonage, I provide the tube F with an enlargement or air-chamber P, which I have found will prevent the formation of a vacuum to such an extent that the trap G will not be emptied or siphoned out. 75

The water-closet bowl A in Fig. 1 is shown provided with a stopper C, connected to the cover (not shown) by a link D, and with a valve N, having the links M R, as described in my United States Patent No. 418,580, of 80 December 31, 1889. When the water-closet is not in use, the valve N rests against the tube F and prevents foul gas passing from the outlet H into the tube F. When the water-closet is in use, the valve N is temporarily 85 moved to the position shown in broken lines in Fig. 1, leaving the tube F temporarily open. As the valve N hangs loosely against the tube F all the time the water-closet is not in use, said valve does not prevent escape of 90 water from the tube F in case of an overflow, while at the same time said valve N prevents foul gas entering the tube F, and thus both ends of the overflow are hermetically sealed, even in case the water in the cup or trap is 95 evaporated because of long non-usage.

My invention is applicable in various places besides water-closets or wash-basins—as, for example, in bath-tubs, wash-tubs, and other receptacles.

What I claim as new, and desire to secure by Letters Patent, is—

1. As a new article of manufacture, an overflow-trap for bowls or receptacles constructed

to maintain a body of water, in combination with a jet I, made to supply fresh water to the upper part of the trap every time the receptacle is being used, substantially as described.

5 2. The combination, with a bowl or receptacle having an overflow-opening and a bottom outlet, of a cup arranged to receive the overflow-water, a tube leading from the cup, having a trap-bend and connected with the 10 bottom outlet of the bowl or receptacle, a ball or float valve located in the cup to close the trap-tube, a valve for closing the end of the trap-tube which connects with the bottom outlet, and a jet for supplying fresh wa- 15 ter to the cup whenever the bowl or receptacle is used, substantially as described.

3. As a new article of manufacture, an over-flow-trap for bowls or receptacles constructed to maintain a body of water, in combination with a jet I, made to supply fresh water to the 20 upper part of the trap every time the bowl or receptacle is being used, said trap having an outlet provided with an air-chamber P to prevent emptying or siphonage of said trap, substantially as described. 25

In testimony whereof I have hereunto set my hand in the presence of two subscribing witnesses.

WM. S. MAYO.
